(57) **CLAIM**

The ornamental design for a truss/joist hand held power saw guide with clamping means, as shown and described.

DESCRIPTION

FIG. 1 is a top view of a truss/joist hand held power saw guide with clamping means showing my new design;
 FIG. 2 is a front end view thereof;
 FIG. 3 is a rear end view thereof;
 FIG. 4 is a right side view thereof;
 FIG. 5 is a left side view thereof; and,
 FIG. 6 is a bottom view thereof.
